Primary Examiner — Llorellys Martinez*(74) Attorney, Agent, or Firm* — ScienBiziP, P.C.(57) **CLAIM**

The ornamental design for a bracelet, as shown and described.

DESCRIPTION

FIG. 1 is a front and top perspective view of a bracelet, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view thereof, taken from encircled portion 9 in FIG. 1.

The broken lines in the figures illustrate portions of the bracelet that form no part of the claimed design. The dash-dot-dash broken lines of FIGS. 1 and 9 are included to show a partially enlarged view only and form no part of the claimed design.
